UNITED STATES PATENT OFFICE

150,180

DESIGN FOR A TARGET

Burnley Weaver, Asheville, N. C.

Application December 30, 1946, Serial No. 135,845

Term of patent 3½ years

(Cl. D30—1)

To all whom it may concern:

Be it known that I, Burnley Weaver, a citizen of the United States, residing at Asheville, in the county of Buncombe and State of North Carolina, have invented a new, original, and ornamental Design for Targets, of which the following is a specification, reference being had to the accompanying drawing, forming part thereof.

The figure is a face view of a target, showing my new design.

The target of the present design is thin and substantially flat.

I claim:

The ornamental design for a target, as shown and described.

BURNLEY WEAVER.
